UNITED STATES PATENT OFFICE.

HERBERT TOWNSEND, OF GLOUCESTER, NEW JERSEY, AND WILLIAM B. DIXON, OF NICETOWN, PENNSYLVANIA.

HOT-AIR HEATER.

1,309,000.

Specification of Letters Patent.

Patented July 8, 1919.

Application filed September 4, 1917. Serial No. 189,482.

To all whom it may concern:

Be it known that we, HERBERT TOWNSEND, a subject of the King of England, residing at Gloucester, in the county of Camden and 5 State of New Jersey, and WILLIAM B. DIXON, a citizen of the United States, residing at Nicetown, in the county of Philadelphia and State of Pennsylvania, have invented new and useful Improvements in 10 Hot-Air Heaters, of which the following is a specification.

Our invention relates to new and useful improvements in hot air heaters, and has for its object to provide an exceedingly simple 15 and effective device of this character whereby the air is caused to circulate within the heater in a circuitous way, so as to be raised to a very high temperature by absorbing the heat at different points, which is thrown 20 off from the burner.

A still further object of the invention is to provide a heater of the class described having an outlet opening, above which is situated a hood or canopy for spreading the 25 hot air and causing the same to flow downward as it leaves the hood.

With these ends in view, this invention consists in the details of construction and combination of elements hereinafter set 30 forth and then specifically designated by the claim.

In order that those skilled in the art to which this invention appertains may understand how to make and use the same, we 35 will describe its construction in detail, referring by numerals to the accompanying drawing forming a part of this application, in which—

The figure is a view of the heater in vertical section.

In carrying out our invention as here embodied 2 represents the outer shell consisting of a bottom 3 having a central opening 4, side walls 5 and a top 6. Extending from 45 the bottom wall 3 to a point some distance from the top 6, and surrounding the opening 4 is an upwardly projecting stack 7, the same being spaced some distance from the side walls 5.

Within the heater is a partition 8 which is located between the outer walls 5 and the stack 7, the same being spaced from both the stack and said side walls and extending from the bottom 3 to a point adjacent the 55 top 6 and intermediate the space between

the top of the stack 7 and the top wall 6. The walls of the partition are provided with openings 10 at the bottom thereof. The space between the partition walls 8 at the top is covered by a top 11 which is spaced 60 from the top end of the stack 7 and the top wall 6 of the heater.

The top wall 6 has an outlet opening 12 which is surrounded by an upwardly projecting flange 13.

The construction of the heater above described produces a circuitous passageway consisting of a chamber 14 within the stack 7, the chamber 15, a portion of which lies above the stack and a portion between the 70 walls of the stack and the partition 8, the chamber 16 between the partition walls 8 and the outer walls 5 of the shell and the chamber 17 between the top 11 and the top wall 6, the latter communicating with the 75 outlet opening 12.

The heater is provided with suitable legs or supports 18 and a burner 19. The burner here shown represents an ordinary gas burner, but it is to be remembered that any 80 kind of fuel may be utilized for producing the required heat, so that this burner may be changed where necessary according to the fuel, which is used.

A hood or canopy 21 is placed over the 85 outlet, and said hood has a central flat portion 22 and an outwardly and downwardly projecting flange 23, so that the hot air issuing from the heater will be given a downward motion as it passes from beneath the 90 hood.

In order that the hood may be properly supported above the heater we provide the same with a depending collar 24 adapted to seat over the flange 13, said collar being of 95 greater length or height than the flange 13 and having openings 25 therein located above the flange 13, when the hood is in place.

In practice the air passing into the heater 100 will pass over the flame of the burner, since said burner is located directly beneath the stack 7, thereby raising the temperature of said air, and as all of the walls of the heater have been heated by the flame from the 105 burner, the air will absorb the heat from the walls of the stack 7, as it passes through the chamber 14, then from the top 11 as it passes from the stack into the chamber 15, where it is caused to flow downward; then from 110

the partition walls 8 and the walls of the stack 7; then from the bottom 3 as it passes through the openings 10 from the chamber 15 to the chamber 16; then from the partition walls 8 and the outer walls 5, as it passes upward through the chamber 16 and again from the top 11 as well as any heat that may be contained in the top wall 6 as it passes through the chamber 17 to the 10 outlet 12 from where it is thrown out into the room in a slightly downward direction by the hood 23.

It has been found that as the air passes through the circuitous passageway formed 15 by the different chambers, the same is sufficiently agitated or broken up to absorb a great amount of heat, and because of the large heating area provided by the construction here shown, the air is raised to a much 20 higher temperature than heaters of ordinary construction, and it has also been found that because of the large heating surface that the odor ordinarily thrown off by gas burners is almost entirely eliminated.

Of course we do not wish to be limited to 25 the exact details of construction here shown, as these may be varied within the limits of the appended claim without departing from the spirit of our invention.

Having thus fully described our invention, what we claim as new and useful, is—

A hot air heater having a circuitous passageway and provided with an outlet opening, a flange surrounding said outlet opening, a hood having a central flat portion and a downwardly and outwardly projecting flange and a depending collar carried by the hood and projecting from the central flat portion thereof and adapted to be placed over the flange, said collar being of greater 40 height than said flange and having openings therein located above the upper edge of the flange when the collar is placed thereon.

In testimony whereof, we have hereunto affixed our signatures.

HERBERT TOWNSEND.
WILLIAM B. DIXON.
